EVAPORATOR FOR REFRIGERATING SYSTEMS

Edolph S. Nelson, Larchmont, N. Y., and Arnold D. Stedle, Canton, Ohio, assignors to The Hoover Company, North Canton, Ohio, a corporation of Ohio

Application August 8, 1936, Serial No. 94,941
Renewed May 29, 1940

3 Claims. (Cl. 62—126)

This invention relates to an evaporator construction for use in an absorption refrigeration system of the type employing an inert gas and operating at high internal pressures such as are necessitated when, for example, ammonia is used as the refrigerant medium, water as the absorbent, and hydrogen, nitrogen or other similar gas as the inert pressure equalizing medium.

The problem of constructing an evaporator for an absorption refrigeration system of the type described above is quite different from that encountered in making an evaporator for a compression type refrigerator. For instance, compression machine evaporators fall into two general classifications, namely, the flooded and the dry types. In neither of these two types is it necessary to circulate the liquid refrigerant through the evaporator in any particular manner. Nor is it necessary to provide for the circulation of an inert gas through the evaporator, or to make the evaporator passages sufficiently large to convey a large volume of inert gas, and a relatively small volume of liquid refrigerant. And of course, since inert gas is not present, it is unnecessary to so construct the evaporator that liquid refrigerant will not seal the passages and prevent the flow of inert gas.

Since compression refrigerators operate under low internal pressures as compared to three fluid absorption apparatuses using ammonia as a refrigerant, the problem of selecting a material of sufficient strength to stand high pressures and yet which is easily workable is not present.

Heretofore, absorption refrigerator evaporators, when made from conduit, have been fabricated from a plurality of pre-formed sections of conduit welded or otherwise joined together. Such conduits have been arranged relatively close together and in substantially vertical planes at the sides of a sharp freezing or ice tray chamber.

This mode of construction has many disadvantages. For example, the very cold evaporator conduits are in direct heat exchange relation to the food compartment air of a refrigerator, and in indirect heat exchange relation to the water in the ice trays within the sharp freezing chamber. Consequently, the air is cooled to an undesirably low temperature and the water is frozen too slowly or not at all. Furthermore, the moisture in the box air condenses on the evaporator conduits in the form of frost and reduces the evaporator efficiency very greatly. Frequent defrosting by discontinuing the operation of the refrigerator, and the spoilage of foodstuffs by dehydration is therefore unavoidable.

The present invention provides an evaporator construction which entirely overcomes the disadvantages of constructions heretofore proposed. It is accordingly an object of this invention to

provide an evaporator for a three fluid absorption refrigerator which is simple, economical to fabricate and which has none of the undesirable characteristics or disadvantages of prior known structures.

More specifically, it is an object of the invention to provide an evaporator made from a continuous, jointless conduit bent in such fashion that at least some of the conduit sections are located in close heat exchange relationship to a chamber to be maintained at a low temperature, but in remote heat exchange relationship to a chamber to be maintained at a relatively higher temperature.

Another object of the invention is to provide an evaporator of the type described in which the evaporator conduits are positioned beneath the ice tray supporting shelves and which thus serve to support said shelves.

20 A further object of the invention is to form an evaporator for a three fluid absorption refrigeration apparatus from a continuous conduit bent to provide a plurality of superimposed, horizontally positioned banks each of which banks comprises a plurality of conduit sections spaced apart laterally to support an object to be cooled.

25 A still further object of the invention is to provide an evaporator construction in which the normal flow of liquid refrigerant therethrough will not prevent or seriously interfere with the circulation of the inert gas.

Other objects and advantages reside in certain novel features of the arrangement and construction of parts as will be apparent from the 30 following description taken in connection with the accompanying drawing in which

Figure 1 is a view in perspective of an evaporator assembly in which the present invention is incorporated and illustrating one embodiment thereof.

Figure 2 is a view in perspective of another embodiment of the invention.

Referring to the drawing in detail and first to the structure shown in Figure 1, it will be seen that the evaporator there shown includes a rectangular, metallic box or housing, open at the front and back, the box having side walls 11 and 12, a top 13 and a bottom 14. The box may have one or more central horizontal partitions 15 therein so as to provide a structure adapted to receive ice cube pans or the like for quick freezing the contents thereof.

For transferring heat from the box to some cooling fluid, each of the horizontal surfaces 13, 14 and 15 have a reversely bent pipe secured to the under side thereof.

Thus, in the arrangement of Figure 1 a single pipe is bent to form a number of horizontal conduits below each of the surfaces 13, 14 and 15 and to provide connections therebetween. The

parallel portions of the pipe beneath the top 13 of the box are designated 16 and it will be seen that they are joined alternately at the front and the back by reverse bends. Similar parallel portions of pipe, similarly connected, are shown at 17 beneath the partition 15 in the box, while similar parallel portions 18 are located beneath the bottom 14 of the box.

The right hand one of the parallel conduits 16 below the top 13 of the box may extend out to the rear thereof as shown at 19 and provide means for either the entrance or the exit of the inert gas. A conduit 20 which may supply liquid refrigerant to the evaporator may be connected to this conduit 19 at that point. Likewise the conduit 18 at the extreme left and bottom of the evaporator may extend to the rear thereof as shown at 21 to provide either the entrance or the exit for the inert gas to the evaporator and a liquid conduit 22 may be connected to the bottom thereof to provide a drain for the evaporator. The rear of the conduit 16 at the left hand upper corner of the evaporator may be connected to the left hand conduit 17 at the rear of the evaporator by means of a connecting portion 23 and likewise the right hand parallel portion 17 may be connected to the right hand parallel pipe 18 by means of the connecting portion 24 at the rear of the evaporator. Thus one continuous jointless pipe is provided with a number of bends sufficient to provide a stack of three parallel banks of passageways one above the other. In Figure 1, the connections between banks are shown located at the rear of the evaporator structure. The system could of course be constructed to provide any desired number of parallel banks of coils within the stack.

Any liquid supplied to the upper end of the continuous coil will flow by gravity downwardly therethrough without forming a pocket or seal which would prevent the flow of the inert gas. The coil of pipe provides means for transferring heat directly from the interior of the evaporator box structure to the fluids in the coil, and the box itself constitutes means adapted to receive and conduct heat indirectly from the surrounding air to the fluids within the coil. The exterior of the box or housing may be provided with fins or the like for aiding in this heat transfer if desired.

Figure 2 shows an embodiment of the invention similar to that of Figure 1 except that the box or housing is of a somewhat different shape and the coils are somewhat differently arranged. The central shelf 25 of the box and the lower shelf 26 are provided with offset or vertically extending portions 27 and 28 respectively so that the distance between the upper and lower portions of the box is slightly less at the right half thereof than at the left, as viewed in Figure 2. The shelves thus provided at the right portion of the box structure may be used to support ice cube pans of shallow depth, as for example, those shown at 29 and 30 while the left hand part of the evaporator may support relatively deep pans for freezing ice cream or the like as shown at 31 and 32.

The top of the box structure may be cooled by parallel portions 33 similar to the parallel portions 16 of Figure 1, the central partition 25 of the box may be cooled by parallel conduits 34 and the bottom 26 of the box may be cooled by

parallel conduits 35. In each case the conduits are below the horizontal portion of the box structure which they cool. The return bends in the parallel conduits 34 and 35 at the rear left-hand corner of the casing extend rearwardly beyond the shelf 25 and the bottom plate 26 to accommodate respectively the depressed portions thereof.

In the arrangement shown in Figure 2, the lower portion of the evaporator is at the forward and left hand side thereof and a drain conduit 22 may be connected thereto to drain any liquid which does not evaporate in the evaporator. From the point of connection of the conduit 22, the cooling coil extends upwardly along the left hand wall of the box structure and then to the rear to form the exit or entrance for inert gas as shown at 21.

While only two embodiments of the invention have been shown and described herein it is obvious that many changes may be made without departing from the spirit of the invention or the scope of the annexed claims.

We claim:

1. An evaporator adapted for use in an absorption refrigerating system using inert gas, said evaporator comprising a continuous, jointless conduit for conducting inert gas and a refrigerant and bent to provide sets of interconnected parallel portions in spaced parallel horizontal planes, a sheet metal box associated with said conduit and having horizontal ice tray supporting shelves, one above and in heat exchange relation with each set of said horizontal portions, the arrangement being such that said horizontal conduit portions underlie said shelves, means for conducting inert gas to said conduit and means for conducting liquid refrigerant thereto.

2. An evaporator adapted for use in an absorption refrigerating system using inert gas, said evaporator comprising a continuous pipe for circulating inert gas and a refrigerant and bent to provide sets of interconnected parallel portions in spaced parallel horizontal planes, a sheet metal box associated with said pipe and having horizontal shelves, one above and in heat exchange relation with each set of said horizontal portions, means for conducting inert gas to said pipe and means for conducting liquid refrigerant thereto, said box being deeper on one side than the other to provide an arrangement having large chambers on one side and small chambers on the other side.

3. An evaporator for an absorption refrigerating system using an inert gas and a refrigerant liquid, said evaporator comprising a continuous, jointless conduit of heavy gauge metal for circulating the inert gas and refrigerant, said conduit being bent to provide a plurality of horizontal banks of tubing, each bank having a plurality of straight horizontal lengths of conduit interconnected by at least two return bends and said banks being superimposed one over another and spaced from each other, said continuous conduit between the spaced adjacent banks maintaining said banks in said spaced relation to form supports for shelves, shelves of heat conducting material secured to the upper sides of all of said straight lengths of conduit in each bank, means for conducting inert gas to said conduit, and means for conducting a refrigerant thereto.
